UNITED STATES PATENT OFFICE.

MATHEW V. RUFF, OF SMYRNA, GEORGIA.

STREET-SWEEPER.

No. 884,421.

Specification of Letters Patent. Patented April 14, 1908.

Application filed June 28, 1906. (Serial No. 323,757.)

To all whom it may concern:

Be it known that I, MATHEW V. RUFF, a citizen of the United States, residing at Smyrna, in the county of Cobb and State of Georgia, have invented a new and useful 5 Street-Sweeper, of which the following is a specification.

This invention relates to a street sweeper of that character adapted to be attached to the rear end of a dump wagon, and the sweepings are conveyed continuously during the movement of the wagon by an endless belt that elevates the sweepings from the street and dumps the same into the wagon.

The invention has for one of its objects to 15 provide a machine of this character which is of simple and inexpensive construction, efficient and easy to operate and includes a minimum of power transmitting connections, so that friction and the useless consumption 20 of power is considerably reduced, or avoided.

With this object in view, and others, as will appear as the nature of the invention is better understood, the invention comprises the various novel features of construction 25 and arrangement of parts, which will be more fully described hereinafter and set forth with particularity in the claims appended hereto.

In the accompanying drawings, which illustrate one of the embodiments of the invention. Figure 1 is a side elevation of the apparatus in operation, portions of the frame thereof being broken away for the purpose of illustration. Fig. 2 is a plan view with a portion of the casing of the apparatus broken 35 away. Fig. 3 is a detail elevation showing one manner of yieldingly supporting the ends of the main brush.

Corresponding parts in the several figures are indicated throughout by similar characters of reference.

Referring to the drawings, A designates the frame of the sweeper at opposite ends of which are arranged the front and rear axles 2 and 3. Intermediate the axles, and arranged 45 with its shaft 4 parallel to the latter, is a main rotary broom or brush 5, the ends of the shaft thereof being mounted in the main frame A at the sides 6 thereof. The sides 6 are preferably made solid from a point adjacent the 50 rear of the broom 5 to the front, so as to prevent dirt and dust from being swept outwardly in a lateral direction from the machine. At the rear of the brush, the sides 6 are inset, as indicated at 7, so as to permit 55 the rear wheels 8 of the machine to be set in

or disposed behind the drum. This permits the machine to be run close along the curbstone without the adjacent rear wheel interfering, so that the gutters of the street can also be cleaned by the machine, thereby doing away with the manual cleaning of the sweepings from the gutters. The main brush 5 is adapted to be driven by the rear wheels or axle, so that the draft of the wagon may be employed as a motive power. For this purpose, one or more sprocket and chain drives are employed, each comprising a large sprocket wheel on the end of the rear axle, designated by 9, and a chain 10 coöperating therewith, which rotates the main brush by 60 means of a small sprocket 11 on the shaft thereof. By this means, the main broom is driven at a relatively high speed.

In order to keep the main brush clean and prevent dirt from being carried over to the 75 rear thereby, an auxiliary rotary brush 12 is provided at a point slightly above and in front of the main brush, the bristles of both brushes being in contact. By preference, the auxiliary brush is rotated by the same 80 sprocket chain employed to actuate the main brush, which chain is so guided as to rotate the auxiliary brush in the same direction as the main brush. The ends of the shaft 14 of the auxiliary brush are provided with 85 sprockets 15 meshing with the sprocket chains 10. The sprocket chain 10 passes in the direction indicated by the arrows adjacent thereto from the top of the large 90 sprocket 9, forwardly and downwardly under the sprocket 11, and then forwardly and upwardly over the sprocket 15, whence it passes rearwardly and downwardly to the large 95 sprocket 9, so that, as the apparatus is drawn forwardly by the wagon, the two 100 brushes will rotate in a clockwise direction around their shafts and thereby produce movements in opposite directions at their point of contact. It will thus be seen that the auxiliary drum will prevent dirt or other 105 trash adhering to the brush and sweep the same off in a forward direction. As shown in Fig. 2, the sprockets of the brooms and a portion of the sprocket chain are disposed inside the main frame, the side 6 thus forming a shield for the drives.

The sweepings from the main broom, and also from the auxiliary broom, are deposited on an endless conveyer arranged at the front of the machine and extending upwardly in an 110 inclined direction, so as to project at its up-

per end over the tail end of a wagon body, which latter is designated by B, Fig. 1. The conveyer comprises an apron or endless belt 16 that is preferably as wide as the main broom 5 and passes around the front axle 2 at one end and a shaft 17 arranged at the upper end of the inclined extension or neck 18 of the frame A. The exterior surface of the apron is provided with a plurality of spaced strips 20 which form pockets for collecting the sweepings. The conveyer receives its motion directly from the front axle 2 and independently of the rear axle. In other words, the conveyer is driven by the front 15 wheels 21 fixed on the axle 2, thereby simplifying considerably the driving mechanisms of the machine. The upper end of the extension 18 where it projects over the wagon is provided with a discharge mouth 22 by which 20 the conveyer can discharge into the wagon.

Arranged between the lower end of the conveyer and the main brush in an inclined position, and extending across the machine, is a deflecting plate or guide 23 for assisting 25 the discharge of the sweepings from the main broom to the conveyer. The plate may be supported in any desired manner, as for instance, by being pivoted at its ends on the inner surface of the sides 6, as indicated at 24. The plate is preferably pivotally mounted so 30 as to permit the lower edge to be raised or lowered by coming in contact with unevennesses in the street. The plate is supported in an inclined position by resting on stops 35 25 formed by projections or pins extending inwardly from sides 6 of the frame.

As shown in Fig. 3, the main brush and broom 5 is supported with the ends of its shaft in bearing blocks 26 that are guided in 40 a vertical direction in slots 27 in the sides 6 of the frame. On opposite sides of each block are helical springs 28 which permit the broom 5 to move bodily upward or to rise and fall at either end so as to accommodate 45 itself to changes in the surface of the street. By means of the screw and nut adjusting

device 29, the broom can be adjusted from time to time as it wears away.

From the foregoing description, taken in connection with the accompanying drawings, 50 the advantages of the construction and of the method of operation will be readily understood and appreciated by those skilled in the art to which the invention appertains.

I have described the principle of operation 55 of the invention, together with the apparatus, which I now consider to be the best embodiment thereof, but I desire to have it understood that the apparatus shown is merely 60 illustrative and that various changes may be made, when desired, as are within the scope of the invention.

What is claimed is:—

A street sweeper comprising a casing and a 65 neck extending therefrom, sweeping mechanism housed by the casing and including a main and an auxiliary brush, a conveyer arranged within the neck and within the casing, a deflecting plate pivotally supported in an 70 inclined position by the casing and extending from the main brush to a point adjacent to the conveyer, the lower edge of the plate being designed to contact with the surface over which the sweeper is moved, means for 75 limiting the downward movement of the plate, extensions projecting from the casing, a shaft supported by the extensions, traction and sprocket wheels carried by the shaft and lying within the planes of the sides of the 80 casing, and sprocket chain connections between the sprocket wheels and sweeping mechanism, said chain connections being so guided as to rotate the auxiliary brush in the same direction as the main brush.

In testimony that I claim the foregoing as 8 my own, I have hereto affixed my signature in the presence of two witnesses.

MATHEW V. RUFF.
